GOLF PRACTICE DEVICE

Frank B. Hewel, Pittsburgh, Pa.

Application June 30, 1934, Serial No. 733,180

4 Claims. (Cl. 273—35)

My invention relates to athletic or sporting apparatus, and it has particular relation to golf practice devices.

One object of my invention is to provide a device for golf practice which shall be simple and inexpensive in construction but effective and satisfying in operation.

Another object of my invention is to provide a device of the character in question, comprising a ball that is adapted to rotate around both a substantially horizontal and a substantially vertical axis.

A further object of my invention is to provide a golf practice device having a support and a ball mounted on a rigid member secured to the support and adapted to move in a plurality of directions at angles to each other.

Another object of my invention is to provide a golf practice device in which a ball is adapted to swing in a generally horizontal rotary path when hit, the ball being also capable of flying upwardly.

Another object of my invention is to provide a ball assembly mounted to rotate when hit, together with a friction member for effecting a braking action on the ball assembly when rotated.

Other objects of my invention will become evident from the following detailed description, taken in conjunction with the accompanying drawings in which:

Fig. 1, Fig. 2 and Fig. 3 are views, respectively in top plan and in section along the line II—II of Fig. 1 and in side elevation of one member of my golf practice device;

Fig. 4, Fig. 5 and Fig. 6; and Fig. 7, Fig. 8 and Fig. 9 are similar sets of views showing two other members of my device;

Fig. 10 and Fig. 11 are, respectively, views in top plan and in side elevation of the completely assembled apparatus;

Fig. 12 is a view, partly in longitudinal section, taken along the line XII—XII of Fig. 10, of my apparatus; and

Fig. 13 is an enlarged view of the ball assembly shown in the three preceding figures.

Referring to the drawings, the structure here shown comprises an annular base or support 1, a secondary support or tiltable member 2 which is pivotally associated with the base member, a rotary platform or table 3 which is pivotally associated with the tiltable member 2, a golf ball or other strikable member 4 secured to a rigid member 5 which is pivotally associated with the rotary platform 3, and a friction or braking mem-

ber 6 for retarding the rotary motion of the rigid ball-supporting member 5.

The main support or base 1 is provided at opposite portions of its inner annular wall with upstanding lugs or ears 12 through which openings or slots 13 are cut. The annular base is also provided with a plurality of openings or holes 14 for the purpose of permitting the device to be rigidly attached to a floor or the like.

The secondary support or tiltable member 2 is disk-like in form, being provided with two downwardly extending lugs or ears 16 which are pierced by openings or slots 17, a central opening 18 through the disk being also provided.

The rotary platform or table 3 is also disk-like in form, having a pair of upstanding lugs or ears 20 struck out of the material thereof and located eccentrically on the rotary table, that is, to one side of the center thereof, these lugs being pierced with aligned holes 21. A hole or opening 22 is also provided at the center of the platform 3.

As clearly shown in Figs. 10, 11, and 12, the members illustrated in Figs. 1 to 9, inclusive, are assembled as follows: The base or support 1 has its upstanding lugs 12 pivotally secured to the downwardly extending lugs 16 of the tiltable member 2 by means of suitable bolt and nut connections 24, for example, although any other form of pivotal mounting may be employed. By reason of the provision of slots rather than small round holes in the lugs 12 and 16, the height of the tiltable member 2 above the base 1 and also the angle at which the member 2 is tilted with respect to the base 1 may be readily selected by the user, the parts being held in their selected position by means of suitably tightening the bolt and nut connections 24.

The rotary platform or table 3 is placed centrally on top of the tiltable member 2 and a bolt and nut pivotal connection 25, for example, is inserted through the hole 22 in the table 3 and registering hole 18 in the tiltable member 2. Here again any other suitable form of vertical pivotal connection may be employed in lieu of the illustrated bolt and nut connection 25. It should be noted that the bolt and nut connection 25 is a relatively loose one in order to permit the platform 3 to rotate with respect to the tiltable member 2.

The ball-supporting rod 5 is provided at one end with a bend or loop 27 and is threaded, as indicated at 28 in Fig. 13, at the other end. This threaded end extends into a hole in the ball device 4 at the bottom of which hole a suitable nut 29 has been disposed. By screwing the threaded

portion 28 of the rod 5 into the nut 29 and tightening another nut 30, previously threaded on the end 28, against the surface of the ball, a suitably rugged and otherwise satisfactory assembly 5 of the ball on the rod is provided.

A stub shaft or other pivotal member 26 is employed as a pivotal connection for the looped end 27 of the rod 5 which is placed between the upstanding lugs 20 of the rotary platform 3. The 10 stub shaft or pin 26 is inserted through the opening 21 in one of the lugs, then through the loop 27 and finally through the opening 21 in the other lug, after which suitable provision is made for holding the pin in place as by the illustrated cotter pin 31. It will be understood, however, that any other suitable horizontal pivotal connection 15 between the ball-supporting rod 5 and the rotary table 3 may be employed.

The breaking device 6 comprises a friction 20 member, such as a block of rubber, secured near the periphery of the tiltable member 2 by means of rivets or pins 32 and preferably having bevelled or rounded ends. The height of the block 6 is such as to normally permit one portion of the ball-supporting rod 5 to rest thereon when the ball 4 is not resting on the floor. The purpose 25 of this braking device 6 will be hereinafter pointed out.

Assuming that the apparatus occupies the position shown in Figs. 10 and 11, for example, the person using my golf practice device assumes his usual stance opposite the ball 4, using whatever golf club he desires, and strikes the ball with 30 whatever force he desires on the one side or the other of the ball 4, as indicated by the arrows in Fig. 10, depending upon whether the player is right-handed or left-handed, as will be understood. As a result of the impact of the club head on the ball, the ball 4, the rod 5 and the rotary 35 table 3 to which the rod is attached swing in a general horizontal rotary path around the pivotal connection 25. At the same time, on account of the looped end 27 of the rod 5 being horizontally pivotally connected to the rotary table 3, the ball 4 may fly upwardly at various angles following a resultant path based upon the relative forces applied thereto during the stroke in a substantially horizontal and a substantially vertical direction.

50 By reason of the illustrated structure wherein ball 4 is capable of motion around both a vertical and a horizontal axis, it will be noted that the ball 4 tends to take the same natural angle of flight dependent upon the particular face angle 55 of the club that is used (driver, midiron, mashie, etc.) that the ball would naturally take if free and hit by the same club. Thus, although my device is rugged in construction and capable of exact adjustments, nevertheless by reason of the 60 provision of the horizontal and vertical axes in question, no undue strain is applied to the rigid ball-supporting rod 5 and thus there is no tendency to break or bend the same, which would be the case if only a vertical rotational axis were 65 provided.

As the ball continues to rotate after being struck, it, of course, gradually sinks down to lower planes and eventually the rod 5 engages the

friction member or rubber block 6, once for each complete rotation thereof. By reason of the provision of this friction or braking member, the ball assembly tends to rapidly decelerate and stop after the rod 5 once begins to contact with the braking member 6. 5

It will be seen that I have thus provided a simple and yet very effective and satisfying golf 10 practice device which is capable of being used in a limited space indoors and in which the ball, after being struck by any selected club, tends to take a path of flight corresponding to the free 15 path that it would assume if hit by the same club, this result being achieved by reason of the provision of both a horizontal and a vertical axis in 20 connection with the ball assembly.

In addition to exercising substantially all of the muscles of the body and thus constituting an apparatus of general athletic value, it should be noted that my advice is beneficial in improving 25 one's golf game, inasmuch as it tends to eliminate one of the main faults of the average player, namely, looking up or raising one's head when striking the ball: inasmuch as the ball does not travel up and away, but remains within the range 30 of vision of the player.

I do not wish to be restricted to the specific structural details or arrangement of parts herein set forth, as various modifications thereof may be effected without departing from the spirit and 35 scope of my invention. I desire, therefore, that only such limitations shall be imposed thereon as are indicated in the appended claims.

I claim as my invention:

1. A golf practice device comprising a support, 35 a secondary support pivotally secured to said support adapted to tilt relative thereto, means for retaining said secondary support in a selected tilted position, a rotatable platform attached to said secondary support, and a ball having a horizontal pivotal connection with said platform.

2. A golf practice device comprising a support, a tiltable member having a horizontal pivotal connection therewith, means for retaining said member in a selected tilted position, a platform 45 having a vertical pivotal connection with said member, and a ball having a horizontal pivotal connection with said platform.

3. A golf practice device comprising a support 50 having upstanding lugs, a tiltable member having downwardly extending lugs pivotally secured to the first-named lugs, a platform having a vertical pivotal connection with said member and having upstanding lugs, and a ball having a pivotal connection with said last-named lugs.

4. A golf practice device comprising a support having upstanding side lugs, a tiltable member having downwardly extending side lugs pivotally secured to the first-named lugs, a platform having a central vertical pivotal connection with said member and having a pair of aligned upstanding lugs located at one side of its center, a rod having a looped end pivotally horizontally connected to said last-named lugs, and a ball secured to the 60 other end of said rod.

FRANK B. HEWEL.
